STOPPERING AND REGULATING DEVICE
FOR CONTAINERS

Hubert Mackenzie Salmond, Fareham, England

Application October 23, 1939, Serial No. 300,835
In Great Britain February 22, 1939

9 Claims. (Cl. 221—73.5)

The invention relates to stoppering devices for fluid containers, and particularly to stoppering devices for containers for storing fluid under pressure, such as the metal bottles used for storing certain fire extinguishing liquids under gas pressure.

The principal object of the invention is to provide an improved construction of stoppering device for containers of the type which are hermetically sealed after charging, such that the hermetic seal may be destroyed to effect discharge of the fluid contents with a minimum delay, and that after destruction, a portion of the device which is broken off to destroy the seal is employed for reclosing the container after the required amount of fluid has been discharged.

Another object of the invention is to provide such a stoppering device which may be used to reopen the container after reclosure, and if necessary to reclose the container again after further use.

A further object of the invention is to provide a stoppering device which consists of a closure plug having a frangible stem portion adapted to be fractured off to unseal a bore therein for the fluid, and thereafter to be forced into the opened bore to reclose the container.

Yet a further object of the invention is to provide a stoppering device consisting of a closure plug having a frangible portion of such a nature that it may be fractured off to unseal a bore in the plug, thereby forming a crater at the end of the bore into which the fractured off portion may be forced to reclose the container.

A still further object of the invention is to provide a closure plug forming a stoppering device, which plug is formed with a frangible stem portion which after fracture from the plug to unseal a bore therein for the liquid, may be forced into the opened bore to reclose the container.

The foregoing and other objects of the invention will be apparent from the following description of a preferred constructional form of stoppering device according to the invention, read in conjunction with the annexed drawings.

In the drawings, Figure 1 is a vertical elevation of a container for fire extinguishing liquid equipped with the stoppering device.

Figure 2 is an enlarged view of the stoppering device in cross-section shown in Figure 1, and showing the stoppering device before fracture.

Figure 3 is a similar view to Figure 2, but shows the stoppering device after fracture and during opening of the container and

Figure 4 is another view similar to Figure 2,

but showing the stoppering device after fracture and during subsequent reclosure of the container.

Referring to the drawings, Figure 1 shows a fire extinguishing fluid container 1 of the solid drawn metal type which is about three-quarters filled with liquid methyl bromide. The container is then charged with nitrogen or other inert gas to a pressure of about 60 pounds per square inch and sealed. For this purpose, the neck of the container is screw-threaded externally to accommodate a closure cap 2 having a central boss 3 (Figure 2) thereon which has a concentric passageway therethrough for sealing by a closure plug 4.

In order to seal the passageway hermetically, it is formed at its upper end with a concentric recess 5 formed with an inverted V-sectioned base 6 forming a circular ridge on which is placed a suitable washer 7. The plug 4 is formed with a corresponding flange 8 having a V-sectioned rim depending therefrom which engages the upper side of the washer 7 and forms therewith a fluid-tight joint when the plug is screwed into the boss 3.

The plug 4 is of hexagonal cross-section, and is recessed about mid-way along its unscrewed portion by a circumferential groove of somewhat V-section, so as to provide a short cylindrical stem 9. The lower portion of the plug is bored from the screwed end to within about ten to fifteen thousandths of an inch from the lower end of the stem 9, by a bore 10 of about $\frac{3}{32}$ " to $\frac{1}{8}$ " in diameter, which is about the same diameter or slightly larger than the stem 9. However the stem 9 may fit into the bore 10 by what is known as a "force fit" and in this case the stem 9 is about 0.001" as a maximum to 0.0005" minimum in excess in diameter to the bore 10. In practice it is desired to make the stem 9 about the same or slightly less than the bore 10 so that the sealing is formed between the conical portion of the fractured off portion of part 4 and the point of fracture 23, somewhat as shown in Fig. 4, and owing to the pressure with which the parts are

forced together a smooth conical seating is formed at 28 which forms a very effective and liquid-tight seal. It is furthermore a fact that the material at the lower portion of part 4 is forced into contact with stem 9 owing to the deformation of the material at 28 so as to virtually seal the parts together again to the extent that if parts 23, 25 and 27 are removed from the extinguisher the fractured off portion of part 4 will remain securely locked in the fixed portion of this part.

Figure 2 is an enlarged view of the stoppering device in cross-section shown in Figure 1, and showing the stoppering device before fracture. Figure 3 is a similar view to Figure 2, but shows the stoppering device after fracture and during opening of the container and Figure 4 is another view similar to Figure 2,

The open end of the bore 10 is enlarged to accommodate one end of a delivery tube 11, which extends within the container 1 to near the lower end thereof, and serves to deliver the fluid in the container under the pressure of the gas.

The upper or head portion of the plug is bored concentrically, and the bore is screw-threaded with a left handed screw-thread 12 which is engaged by a left-handed screwed portion 13 of an operating spindle 14.

The plug 4 is enclosed within a sleeve member 15, the inner side of which is hexagonal shaped similar to the external surface of the plug, but somewhat greater in size, so that the parts are easily slidable relatively to one another. The sleeve member is provided at its lower end with a conical flange 16 whereby it is secured on the cap 2 by a union nut 17 engaging a screw-thread on the external side of the boss 3, a suitable washer 18 being interposed between the bottom end face of the sleeve member and the upper end face of the boss 3.

In the side of the sleeve member, a screwed passageway is provided in which is secured a discharge nozzle 19 for the fluid, a suitable washer 20 being interposed between the outside of the sleeve member and a flange on the nozzle pipe.

The upper end of the sleeve member 15 is screw-threaded externally, and a closure cap 21 is screwed thereon with the interposition of a washer 22, to form a fluid-tight joint. The cap 21 is formed with a central boss 23 which is bored centrally and screw-threaded with a right-handed screw-thread 24 for engagement by the right-handed screwed portion 25 of the operating spindle 14 in a substantially fluid-tight manner.

The outer end 26 of the operating spindle is squared as shown, and is fitted with an operating handle 27 of a convenient size.

When it is desired to use the fire extinguisher, the nozzle is directed towards the fire, and the handle 27 is rotated in the anti-clockwise direction through one half to one complete turn. This rotation causes the head portion of the plug 4 to be fractured off from the body of the plug at the junction of the bottom end of the stem 9 with the body portion, as shown in Figure 3. As the fracture is a sheer fracture, an orifice is formed at the upper end of the bore 10 as shown at 28, whilst the lower end of the broken off stem 9 has the form of a punch.

On breakage of the frangible portion of the plug 4, the fluid within the container is enabled to be discharged into the sleeve member and out through the nozzle 19 under full pressure of the gas in the container, so that there is no delay in supplying fire extinguishing liquid.

After sufficient liquid has been delivered from the container to extinguish the fire, and further liquid is not desired, the handle 27 may be rotated in a clockwise direction one to two turns. By such rotation of the handle, the fractured off head with its depending stem is moved towards the body portion of the plug, the punch shaped end 29 of the stem 9 ultimately entering the orifice 28 formed at the top of the bore 10. On further rotation of the handle, the stem 9 is forced into the bore to seal the container, and this movement may be continued until the coned upper portion of the head engages the orifice 28 at the top end of the bore, as shown in Figure 4. The top of orifice 28 forms an effective valve seating for the coned portion of the head, and an efficient fluid-tight joint is made between the body of the plug and the severed off head portion

thereof, which prevents leakage of fluid from the container until the container can be removed for refilling.

If however it is desired to discharge further fluid after reclosure of the container, it is only necessary to rotate the handle 27 in an anti-clockwise direction to withdraw the stem 9 from the bore 10, when the liquid in the container will again be discharged from the nozzle pipe 19 under full pressure of the gas in the container. This discharge can be interrupted when desired by again rotating the handle 27 in the clockwise direction until the stem 9 is again forced into the bore 10, if necessary, to its fullest extent.

When the container is finally returned for refilling, the only part requiring replacement is the closure plug 4 which has been fractured to unseal the container.

It will be evident that the arrangement hereinbefore described by way of example, may be modified within the scope of the invention. For instance, instead of enclosing the plug 4 in a sleeve which prevents its rotation, the interior of the sleeve may be cylindrical in form as also may be the exterior of the plug. In such a case, the stem 9 may be severed from the body of the plug by a combination of tension and torsion forces as the head of the plug may tend to rotate somewhat with the spindle 14.

In another form, the head portion of the plug may be screw-threaded on the exterior for engagement by an internally screw-threaded lower end of the operating spindle 14, and in yet another form, these parts may be connected by means of a coarse threaded screw-thread on one part engaged by a pair of diametrically arranged pins on the other part.

Broadly therefore, the invention embraces any suitable means for removing the stem 9 from the body of the plug 4, and thereafter reclosing the orifice 23 by forcing the stem into the bore 10.

Having thus fully described my invention, what I claim as new and desire to protect by Letters Patent is:

1. Stoppering device for containers comprising a closure plug having a bore therein extending longitudinally almost through said plug, a frangible stem portion thereon over the inner end of said bore, said stem having a diameter smaller than said bore, and means for fracturing said stem portion off said plug to unseal said bore in said plug, and for thereafter forcing said fractured off stem portion into said bore to reclose said container.

2. Stoppering device for containers comprising a closure plug having a bore therein extending longitudinally almost through said plug, a frangible stem portion thereon over the inner end of said bore, said stem having a diameter smaller than said bore, and means for forcing said stem portion axially off said plug in tension to unseal said bore, and for thereafter forcing said fractured off stem portion axially into said bore to reclose said container.

3. Stoppering device for containers comprising a closure plug, a substantially circular stem portion at one end of said plug integral therewith, said plug having a concentric bore extending from the other end thereof to near said stem portion, said stem being of a size slightly smaller than the cross-section of said bore, and means for fracturing said stem from said plug to unseal said plug and thereafter forcing said stem tightly into the said bore unsealed by said fracturing operation.

4. Stoppering device for containers comprising a closure plug, a concentric solid stem portion at one end thereof, a concentric bore of slightly greater cross-section in said plug and extending therein from the other end thereof to near the said stem, a frangible portion in said plug between said stem portion and the inner end of said bore, and means associated with said stem adapted on primary operation thereof forcibly to separate said stem portion from said plug by fracturing said frangible portion, thereby extending said bore throughout said plug, and on secondary operation thereof to force said separated stem portion into said unsealed bore to reclose said container.

5. Stoppering device for containers comprising a closure plug, a concentric, solid, cylindrical, integral stem portion at one end thereof, a concentric bore in said plug one thousandth of an inch less in diameter than the diameter of said stem portion and extending therein from the other end of said plug to within ten thousandths of an inch of the root portion of said stem portion, and means associated with said stem portion for forcibly separating said stem portion from said plug, and for thereafter forcing said separated stem portion into said bore to reclose said container.

6. Stoppering device for containers comprising a closure plug, a concentric, solid, cylindrical, integral stem portion at one end thereof, a screw-thread on said stem, a concentric bore in said plug slightly greater in diameter than the diameter of said stem portion and extending in said plug from the other end thereof to close to the root portion of said stem portion, means for axially moving said stem portion and for restraining it against rotation, and an internally screw-threaded member engaging said screwed portion of said stem portion and mounted for rotation in an abutment fixed relatively to said container for axially moving said stem portion.

7. Stoppering device for containers comprising a screw-threaded closure plug, a concentric solid cylindrical integral stem portion at one end of said plug, an enlarged head on said stem, of non-circular cross section, a concentric screw-threaded bore in said head, a concentric bore in said plug slightly greater in diameter than said stem and extending in said plug from the other end thereof to near the root portion of said stem, a

5 sleeve surrounding said plug and head portion and secured relatively to said plug, said head portion being slidable in said sleeve member, an abutment at one end of said sleeve, a spindle rotatably mounted in said abutment and having a screw-threaded end portion engaging said internally screwed bore in said head.

8. Stoppering device for containers comprising a screw-threaded closure plug, a concentric integral stem portion at one end of said plug, an enlarged head on said stem of non-circular cross section, a concentric screw-threaded bore in said head, a concentric bore in said plug slightly greater in diameter than said stem and extending in said plug from the other end thereof to near the root portion of said stem, a sleeve surrounding said plug and head and secured at one end in a fluid-tight manner to said container, the interior of said sleeve being of similar cross-section to said head but of slightly greater size, a closure gland at the free end of said sleeve, a discharge nozzle in the side of said sleeve, a spindle screwed at one end to engage said screwed bore in said head, and screwed at its other end 20 in the opposite direction, a screwed bore in said gland for said oppositely screwed portion of said spindle and a handle on the exterior end of said spindle.

9. Stoppering device for containers comprising a screw-threaded closure plug, a concentric integral stem portion at the outer end of said plug of $\frac{1}{8}$ inch plus one thousandth of an inch diameter, an enlarged head on said stem of hexagonal, cross-section, a concentric screw-threaded bore in said head, a concentric bore in said plug of $\frac{1}{8}$ inch diameter extending from the inner end of said plug to within ten thousandths of an inch to the root of said stem, a hexagonal sectioned sleeve surrounding said plug, stem and head, of slightly greater size than said head, and secured at one end in a fluid-tight manner to said container, a discharge nozzle pipe in said sleeve, a closure gland at the outer end of said sleeve, a concentric bore in said gland, said bore being screw-threaded in the opposite direction to said bore in said head, an operating spindle screwed at one end to engage said screwed bore in said head and at its other end to engage said screwed bore in said gland, and a handle on the external end of said operating spindle.

HUBERT MACKENZIE SALMOND.
